(57) **CLAIM**

The ornamental design for a coupling clip for an enclosure, as shown and described.

DESCRIPTION

FIG. 1 is a rear perspective view of a coupling clip for an enclosure, showing my new design;

FIG. 2 is a left-side elevation view of the coupling clip for an enclosure of FIG. 1;

FIG. 3 is a right-side elevation view of the coupling clip for an enclosure of FIG. 1;

FIG. 4 is a front elevation view of the coupling clip for an enclosure of FIG. 1;

FIG. 5 is a rear elevation view of the coupling clip for an enclosure of FIG. 1;

FIG. 6 is a top plan view of the coupling clip for an enclosure of FIG. 1;

FIG. 7 is a bottom plan view of the coupling clip for an enclosure of FIG. 1; and,

FIG. 8 is a bottom perspective view of an enclosure that includes the coupling clip for an enclosure of FIG. 1.
